TROLLEY POLE HEAD

Theodore R. Rideout, Pittsburgh, Pa., assignor to Westinghouse Electric & Manufacturing Company, East Pittsburgh, Pa., a corporation of Pennsylvania

Original application July 24, 1941, Serial No. 403,801. Divided and this application December 12, 1942, Serial No. 468,760

6 Claims. (Cl. 287—85)

My invention relates, generally, to current collectors and has reference, in particular, to a trolley pole head for use on trolley buses or other vehicles for collecting current from an overhead conductor.

This is a division of my application Serial No. 403,801, filed on July 24, 1941, now Patent No. 2,326,065, dated August 3, 1943, and assigned to the assignee of the present invention.

Generally stated, it is an object of my invention to provide a simple and inexpensive trolley pole head which is inexpensive to manufacture and easy to install.

More specifically, it is an object of my invention to provide a trolley pole head having an improved body member for supporting a pivotally mounted slider shoe and also having a detachable resilient connection with a trolley pole or trolley pole extension for minimizing shocks when the current collector strikes an irregularity in the overhead system or some other obstruction.

Another object of my invention is to provide a resilient pole head mounting wherein a resilient bushing and connecting means may be positioned between the trolley pole or trolley pole extension and the body member of the pole head.

Still another object of my invention is to provide an easily detachable connection between a pole head body member and the resilient material of a pole head mounting.

Yet another object of my invention is to provide for detachably connecting a trolley pole head to a resilient member on a trolley pole member.

It is also an object of my invention to provide an inexpensive pole head structure having a resilient mounting with a metallic member recessed in a resilient material for effecting a detachable connection between the resilient material and one of the resiliently related parts.

Other objects will in part be obvious, and will in part appear hereinafter.

In practicing my invention a simple and inexpensive pole head body structure for supporting a slider shoe or other current collector device on a trolley pole may comprise a tubular member to receive an elongated trolley pole support member and having a socket for receiving a slider shoe support member. A resilient guard member having an inclined front guard surface is interposed between the body member and the slider shoe, and is secured thereto by means of the slider shoe support. A resilient bushing may be interposed between the body portion of the

pole head and the trolley pole support member having metallic securing means formed therein to which the pole head body member may be detachably secured.

For a more complete understanding of the nature and scope of my invention reference may be had to the following detailed description, which may be read in connection with the accompanying drawing in which:

Fig. 1 is a side elevational view of a trolley pole head embodying the principal features of the invention;

Fig. 2 is a rear elevational view partly broken out and partly in section of the pole head of Fig. 1;

Fig. 3 is a partly sectioned side elevational view of the pole head of Fig. 1 with the slider shoe and guard member removed; and

Fig. 4 is a sectional view taken along the line IV—IV of Fig. 3.

Referring to Figs. 1 and 2, the reference numeral 10 may denote generally a trolley pole head having a slider shoe 11 detachably secured to a swivel 12 by bolts 13 and pivotally mounted on a substantially vertical support member 14 for engaging a trolley conductor 15. The support member 14 may be mounted on a trolley pole (not shown) by means of a body member 16, which may be secured to the trolley pole by means of an elongated trolley pole extension or support member 17 which is adapted to fit within the end of the trolley pole in a well known manner. The body member 16 may be provided with a socket member 18 for receiving the support member 14. A suitable guard member 19 may be positioned between the slider shoe and the body member 16 to prevent the slider shoe from becoming entangled in support wires and the like.

As shown in Figs. 1 and 3, the pole head body member 16 may comprise an elongated tubular member 20 having openings 21 and 22 therein so positioned on opposite sides adjacent one end as to receive the tubular socket member 18 which may be secured thereto in inclined relation, in any suitable manner such as by welding.

In order to provide a resilient connection between the pole head body member 16 and trolley pole extension or support member 17 and insulate them from each other, a bushing 23 of a suitable resilient material such as, for example, rubber, synthetic rubber, or any other such material, may be interposed between the tubular body member 20 and the support member 17 so that it is substantially surrounded by the

body member. Deformation of the bushing is thereby limited, since the principal stresses will be those of compression. The support member 17 may be provided with a recess or notch 24 on one side and the bushing 23 may be provided with a corresponding protuberance 25 positioned in the recess to assist in locking the bushing to the support member.

In order to detachably secure the body member 16 to the bushing 23, the outer surface of the bushing may be provided with recessed portions 26 as shown in Figs. 3 and 4 for receiving connecting means such as the metal plates 27. The plates 27 may be merely positioned in the recesses after they are formed; they may be formed integral therewith during the molding process or they may be secured thereto in any other suitable manner. The recesses 26 may be so positioned relative to one another as to leave ribs 28 of the resilient material therebetween which resist movement of the plates 27 peripherally on the bushing. Screws 30 may be utilized to secure the body member 16 to the plates 27, thereby detachably securing the pole head body member 16 to the trolley pole support or extension 17 and affording a yielding connection therewith. A back up plate 32 may be provided within the tubular member 20, if desired, to prevent undue deformation of the resilient material 23 and thus increase the resistance of the resilient material against the shear stresses set up when forces are applied to the body member 16 tending to separate it from the trolley pole extension or support member 17. In order to provide an additional connection between the tubular member 20 and the resilient material 23, the tubular member 20 may be deformed at one or more places to provide protuberances 33 on the inner side which interlock with the resilient material and assist in securing the member 20 thereto.

From the above description and accompanying drawing, it will be apparent that I have provided a simplified pole head or current collector which is inexpensive to manufacture and is easy to install. The tubular construction of the body member readily lends itself to the production manufacturing. The resilient mounting of the tubular pole head body member on the trolley pole extension is effected in a simple and inexpensive manner. The connection between the connecting metal plates and the resilient bushing may be permanent by vulcanizing or the like, or they may be merely positioned in the recesses therein, and the tubular body may be easily attached thereto or detached therefrom for repairs. Different current collectors may be used on the same trolley pole extension without any trouble. Since the resilient bushing and securing means are enclosed by the tubular pole head body, deformation of the bushing is minimized and the principal stresses are in compression, which are the more easily resisted. Accidental removal of the pole head from the trolley pole extension is thereby minimized.

Since certain changes may be made in the above description, and different embodiments of the invention may be made without departing from the spirit thereof, it is intended that all

of the matter contained in the above description or shown in the accompanying drawing shall be considered as illustrative and not in a limiting sense.

5 I claim as my invention:

1. The combination in a trolley pole head structure, of a trolley pole extension having a bushing of resilient material positioned about one end, metallic securing means recessed in the resilient material, a relatively thin sheet metal pole head member positioned about at least a portion of the bushing and the securing means, and means projecting through the pole head member detachably securing the pole head member to the securing means.

10 2. A current collector mounting comprising, a trolley pole member, a bushing of resilient material positioned about said trolley pole member, a metallic plate positioned adjacent and secured in substantially fixed relation to the surface of the resilient material, a pole head body member formed of relatively thin sheet metal positioned about the said bushing and plate, and means to detachably secure the pole head body member to the said plate.

15 3. A resilient mounting comprising, an elongated support member, a bushing of a resilient material positioned about a portion of the support member, metallic securing means recessed in the outer surface of the bushing, a socket member positioned about the bushing and metallic securing means, and means detachably securing the securing means to the socket member.

20 35 4. A resilient mounting comprising, an elongated cylindrical body, a substantially cylindrical bushing of a resilient material secured about the body and having a recess in the outer surface thereof, a rigid member positioned in the recess, a tubular body substantially enclosing the bushing, rigid member and a portion of the cylindrical body, and means projectable through a portion of the tubular body detachably connecting the rigid member to the tubular body.

25 40 45 5. A resilient mounting for securing a socket to a support member comprising, an elongated tubular bushing of a resilient material secured to the support member and provided with longitudinally extending ribs and transverse portions of the resilient material defining recesses therein, metal plates positioned in the recesses, a socket substantially enclosing the metal plates and bushing, and screws projecting through the socket into the metal plates to detachably secure the socket about the bushing.

30 50 55 60 65 6. A resilient mounting comprising, an elongated cylindrical support, a substantially cylindrical bushing of resilient material secured about the support adjacent one end and having a plurality of longitudinally extending ribs of the material and peripheral shoulders adjacent the ends defining a plurality of recesses therein, an arcuate metal plate positioned in and substantially filling each recess, a tubular body member positioned about and substantially enclosing the metal plates and bushing, and means connecting the metal plates to the body member.
